PHOTOELECTRIC INTRUSION DETECTOR UNIT

William G. Kahl, Jr., Brookfield, Conn., assignor to
Arrowhead Enterprises, Inc., Bethel, Conn.

Filed Feb. 4, 1971, Ser. No. 112,575

Term of patent 14 years

Int. Cl. D29—99

U.S. Cl. D72—1

Fig. 2.

Fig. 1.

Fig. 3.

Fig. 4.

Fig. 5.

Fig. 6.

FIG. 1 is a perspective view of a photoelectric intrusion detector unit showing my new design;

FIG. 2 is a top plan view thereof on an enlarged scale;

FIG. 3 is a front elevational view thereof on an enlarged scale;

FIG. 4 is a bottom view thereof on an enlarged scale;

FIG. 5 is a side elevational view thereof on an enlarged scale; and

FIG. 6 is a rear elevational view thereof on an enlarged scale.

I claim:

The ornamental design for a photoelectric intrusion detector unit, substantially as shown and described.
